HAIR CURLER

Harry Solloway and Teofil L. Bonkowski,
Los Angeles, Calif.

Application August 20, 1949, Serial No. 111,472

5 Claims. (Cl. 132—41)

1

This invention relates to apparatus for the curling or waving of hair and is directed particularly toward apparatus which is intended to be used in imparting a "permanent wave" to the hair.

It is the principal object of our invention to provide an apparatus for curling the hair which is simple in construction and easily manipulated by an unskilled operator.

Another object of our invention is to provide an apparatus for curling the hair which may be withdrawn from the strand of hair without unwinding the curl.

Another object of our invention is to provide an apparatus of the character described in which there is no danger of hair becoming snagged or snarled.

Other objects and advantages of our invention will appear from the following detailed description of the preferred embodiments thereof shown in the accompanying drawings wherein:

Figure 1 is a perspective view of the preferred form of curler embodying the invention.

Figure 2 is a side elevation of the invention, partly in section.

Figure 3 is a sectional view taken on line 3—3 of Figure 2.

Figure 4 is a sectional view taken on line 4—4 of Figure 2.

Figure 5 is a fragmentary side elevation showing a modified form of the hair-engaging means.

Referring now to the drawings, our invention includes a mandrel generally designated 10, substantially cylindrical in cross-section. Carried on the mandrel 10 and integral therewith are a plurality of longitudinal ribs 11, uniformly curved at one end and terminating at that end in the flange 12 which is also integral with mandrel 10. A relatively short mandrel shaft 13, provided with a flange 14 at the end thereof, is carried axially of the mandrel and integral with the flange 12.

A journal head 15, substantially U-shaped in transverse section, is provided with seat 16 in which mandrel shaft 13 is journaled. Longitudinal motion of the mandrel with respect to the journal head 15 is prevented by means of shoulder 17 against which flange 12 abuts and shoulder 18 against which flange 14 abuts. The legs 19 and 20 of journal head 15 are provided with apertures 21 and 22.

Means are provided to restrict free rotational movement of the mandrel 10 in the journal head 15, and as shown best in Figure 4 this means may include pawl 23 in hood portion 24 of the journal head 15. The pawl 23 may engage in any one of

5 a plurality of depressions 25 each located centrally between a pair of adjacent terminating ribs 11 and around the periphery of the flange 12. An annular slit 26 is provided in the journal head 15 so that the hood portion 24 is separated therefrom, thus allowing a degree of spring action in the hood portion 24. These means provide a ratchet effect, and hence rotational movement of the mandrel 10 may be accomplished only through application of substantial torque to the mandrel 10.

10 Means are provided to lock the hair on the mandrel 10 and to retain the curler in position on the head, and as shown in the drawings this means may include locking bar 27 pivotally connected to the journal head 15 by means of lugs 28 and oppositely disposed base member apertures 21 and 22. The phantom lines in Figure 1 illustrate the locking bar 27 in partially open position. Locking elements 29 and 30 are provided on the locking bar 27 and, when the locking bar 27 is closed, engage in the depression formed between a pair of adjacent ribs 11, thus securely locking the mandrel 10 against rotational movement. The end of the locking bar 27 is curved to form a spring latch member 31 which when engaged with the rounded end portion 32 of the mandrel 10 acts to maintain the curler in closed position. It should be noted that due to the manner in which the ribs 11 are curved the locking element 29 will, when the locking bar 27 is being closed, engage between two adjacent ribs 11 before locking element 30 will so engage, thus providing a form of prelocking means.

15 Hair-engaging means are provided on the mandrel 10, and as shown in the drawings this may include a plurality of teeth 33 carried on an elongated plate 34 integral with the mandrel 10. The teeth 33 are inclined at an angle pointing toward the end portion 32 of the mandrel so as to present no resistance when the curler is longitudinally withdrawn from the curled strand of hair. In order that withdrawal of the curler may be even more facilitated, means are provided for retracting the teeth 33, and as shown in Figure 2 this may include the slot 35 in the mandrel 10. The cross-sectional area of the plate 34 is relatively small in the portion toward the flange 12, thus providing a spring action and hence allowing the teeth 33 to be retracted into the slot 35, as shown by the phantom lines in Figure 2, when pressure is exerted thereon.

20 Figure 5 illustrates a modified form of hair-engaging means. Here the plate 36 is not integral with the mandrel but is formed as a sep-

arate structure. The plate 36 is held in the longitudinal slot 37 in mandrel 38 by means of ears 39 and 40 which abut shoulders 41 and 42 in the mandrel 38. Spring members 43 and 44 integral with the plate 36 allow the teeth 45 to be retracted into the slot 37 when pressure is exerted thereon. Longitudinal movement of the plate 36 is prevented by means of the shoulder 46 against which the end 47 of plate 36 abuts and aperture 48 into which the end portion 49 of spring member 44 projects.

The method for using the above described apparatus is as follows:

The locking bar 27 is disengaged from the mandrel 10 so that the mandrel 10 is free to rotate on the exercise of sufficient torque to overcome the engagement of pawl 23 in the depressions 25. A strand of hair is separated and the end thereof is engaged in the teeth 33. The journal head 15 is held stationary with one hand while the mandrel 10 is rotated so as to curl the strand of hair about the mandrel. When the desired amount of hair has been curled upon the mandrel the locking bar 27 is closed, thus securing the curler in place on the head. The hood portion 24 insures against the possibility of any stray strand of hair being caught or snarled between the end portion of the mandrel and the adjacent portion of the journal head. When the curl has been set for the desired length of time, removal of the curler is accomplished by opening the locking bar 27 and sliding the curler laterally from the curl, thus leaving the strand of curled hair intact. The teeth 33 offer practically no resistance to the withdrawal of the curler due to their angular inclination and to the fact that when the curl is held by the fingers sufficient force is exerted to retract the teeth 33 into the mandrel slot 35.

While we have shown and described a specific embodiment of our invention, we do not limit ourselves to the exact details of construction set forth, and the invention embraces such changes, modifications and equivalents of the parts and their formation and arrangement as come within the purview of the appended claims.

We claim:

1. As an article of manufacture, a hair curling apparatus comprising: a journal head, a mandrel having a shaft journaled in said journal head, said mandrel being relatively uniform in cross-section and having a plurality of longitudinal ribs angularly disposed thereon, and integral therewith, and a locking bar pivotally connected to said journal head, said locking bar having a locking element adjacent each end thereof adapted to engage the depression formed by any two adjacent ribs.

2. As an article of manufacture, a hair curling apparatus comprising: a journal head, a mandrel having a shaft at one end thereof journaled in said journal head, said mandrel being relatively uniform in cross-section and having a plurality of longitudinal ribs angularly disposed about the periphery thereof, a locking bar pivotally connected to said journal head, said locking bar having locking elements adjacent both ends thereof adapted to engage in a depression formed

by any two adjacent ribs, the ribs adjacent the journal head curving outwardly whereby the locking element adjacent the pivoted end of said locking bar will engage in said depression before the locking element adjacent the free end of said locking bar.

3. As an article of manufacture, a hair curling apparatus comprising: a journal head; a mandrel journaled in said journal head and having depressions in one end and longitudinally extending ribs; a pawl on said journal head cooperating with said depressions on said mandrel to restrict free rotational motion of said mandrel with respect to said base member; and a locking member pivotally connected to said journal head and adapted to cooperate with said ribs to lock the mandrel against rotational motion.

4. As an article of manufacture, a hair curling apparatus comprising: a journal head; a mandrel journaled in said journal head for axial rotation therein and having an extended free end; hood means covering the juncture between said journal head and mandrel to prevent snarling of hair between said journal head and said mandrel; hair-engaging means on said mandrel, said hair-engaging means including a plurality of teeth disposed at an angle pointing toward the free end of said mandrel, said teeth being retractable into a slot in said mandrel; and a locking bar pivotally connected to said journal head and extendable over the free end of said mandrel, said locking bar adapted to lock the mandrel against rotational motion and to contain a strand of hair which may be curled about said mandrel.

5. As an article of manufacture, a hair curling apparatus comprising: a journal head; a mandrel journaled in said journal head for axial rotation therein and having a longitudinal slot and longitudinally extending locking formations, the end of said mandrel remote from said journal head being free; hair-engaging means on said mandrel, said hair-engaging means including a spring plate set in said slot, the plate carrying a plurality of hair-engaging teeth directed toward the free end of said mandrel and normally extending exteriorly of said slot but adapted to be retracted into said slot upon the application of a force sufficient to deflect the spring plate; and a locking member pivotally connected to said journal head and adapted to fit over the free end of said mandrel and having means to engage said locking formations thereby to lock the mandrel against rotational motion.

HARRY SOLLOWAY.
